D. GUELBAUM

GRAIN CUTTING MACHINE

Filed Oct. 21, 1922

INVENTOR.

David Guelbaum

UNITED STATES PATENT OFFICE.

DAVID GUELBAUM, OF SYRACUSE, NEW YORK.

GRAIN-CUTTING MACHINE.

Application filed October 21, 1922. Serial No. 598,176.

To all whom it may concern:

Be it known that I, DAVID GUELBAUM, a citizen of the United States, and a resident of Syracuse, in the county of Onondaga and 5 State of New York, have invented a certain new and useful Grain-Cutting Machine, of which the following is a specification.

My invention of a "grain cutting machine" has for its object the cutting up of certain real grains, such as wheat, rye, barley, into particles, coarse or fine, without cracking or crushing of the grains and without powdered wastage, so that the cuttings obtained 10 are less exposed to the drying deodorizing atmospheric action and the nutritive essence 15 of the grains is better preserved, than in other grain disintegrators, and such clean cereal cuttings are therefore better adapted for dietary purposes, especially for the making 20 of bread from un-milled cereal grains.

My invention comprises the above set forth novel features, embodied in combinations and constructions as hereinafter set forth and claimed, and as illustrated in the 25 accompanying drawings, in which similar characters designate the same corresponding parts in all the views.

Fig. 1 is a vertical section of my grain cutting machine.

Fig. 2 is a cross section of the same, showing the cutting edges.

Fig. 3 shows the adaptation of the machine to a belt drive with variable speed.

Fig. 4 shows a modification of the inner cutting cylinder, provided with a separate cutting sheet steel cover.

As seen on Fig. 1, my grain cutting machine consists of the grain hopper 1 having an offset cylindrical flanged top 2 and an 40 open tapered flanged bottom with a supporting ledge 3 inside. Into that bottom of the hopper is fitted in the stationary outer cylinder 4 resting on the ledge 3 and secured by the tap bolts 5. By loosening these bolts the 45 cylinder 4 can easily be taken out and replaced by another one to suit different kinds of grains when desired.

This stationary outer cylinder 4 is provided with longitudinal slots with beveled off edges, as shown on Figs. 1 and 2; the solid strip 6 in the middle of the cylinder, shown on Fig. 1, serves merely as a re-enforcement.

Inside the stationary outer cylinder 4 is 55 fitted slidably the inner rotary cutting cyl-

inder 7, provided with similar longitudinal slots with sharper beveled cutting edges, as shown on Figs. 1 and 2.

The top of the inner cutting cylinder 7 fits into the bottom of the cone shaped cover 8, shown in section on Fig. 1, and is held securely by the tap bolts 9; by loosening these bolts the cutting cylinder can easily be taken out and replaced by another one when desired. The rim 10 at the bottom of the cover 8 loosely overlaps the top of the stationary outer cylinder 4 to protect it from injury, as shown on Fig. 1.

The cone shaped cover 8 terminates at its top with the shoulder 11 and projecting pivot on which is key-seated the hub of the handwheel 12 and secured by the tap bolt and washer 13, as shown on Fig. 1. This hand wheel is provided with the radial arms 14 and the circular rim 15 resting on the flanged offset 2 on top of the grain hopper 1 and fitting slidably into same. The rim 15 of the hand wheel is held fast to its seat by several clips 16 bolted on to the top flange of the hopper, as shown on Fig. 1.

Thus, the hand wheel 12 carrying the cone shaped cover 8 with the cutting cylinder 7 is reliably supported and guided, taking off all side strains from the cutting cylinder. By un-fastening the clips 16, the hand wheel 12 with the cover 8 and the inner cylinder 7 can be bodily taken out of the grain hopper 1.

On the arms 14 of the hand wheel, near its rim 15, are cast on the bosses 17, to one of which is fastened the handle 18 for rotating the hand wheel. To the bottom of these bosses 17 are fastened the scoops or stirrers 19, consisting preferably of twisted plates, as shown on Fig. 1 and in section on Fig. 2. These scoops, rotated by the hand wheel, in the direction shown in plan Fig. 2, shovel and thrust the grains through the longitudinal slots of the outer stationary cylinder 4, the grains being met and cut by the sharp cutting edges of the rotating inner cylinder 7.

One of the clips 16 holding the handwheel fast to its seat is provided at its top with the button headed setscrew 20, piercing through slightly into the rim 15 of the handwheel, for the purpose of holding the handwheel fast to the hopper, when the machine is not working, in such a position, that the strips of the inner cylinder 7 cover the slots

of the outer stationary cylinder 4, and no grains can pass through the slots.

The grain hopper 1 is mounted with its bottom flange on top of the wooden box 21, 5 provided with the drawer 22 inside, for collecting the discharged grain cuttings, as they drop off the inside surface of the cutting cylinder 7.

- The action of the machine is as follows:
- 10 When the machine is not working and the hand wheel 12 is held fast by the button headed setscrew 20, the strips of the inner cylinder 7 cover the slots of the outer cylinder 4, and no grains can pass through.
  - 15 The hopper 1 is then filled with grain, the hand screw 20 is loosened and the hand wheel rotated by the handle 18 in clock wise direction, as shown in plan on Fig. 2. The rotating scoops 19 shovel and thrust the
  - 20 grains through the longitudinal slots of the stationary outer cylinder 4, the projecting and passing grains being met and cut by the rotating cutting knives of the inner cylinder 7.
  - 25 By loosening the fastening bolts of the scoops and turning them to the position shown in dotted line 19' on Fig. 2, the direction of rotation of the hand wheel may be reversed to opposite clock wise motion, and
  - 30 the opposite cutting edges on the inner cylinder are then utilized.

The more cutting knives are passing per minute over the slots of the stationary outer cylinder, the finer evidently will the cuttings be. Therefore, by rotating the hand wheel 12 faster or slower, the obtained grain cuttings will accordingly be finer or coarser, as desired.

Fig. 3 shows the top portion of the machine adapted for a belt drive with variable speed. For that purpose the projecting pivot on top of the cover 8 and the hub of the hand wheel 12 are extended upward, and a step pulley is key seated and setscrewed 45 on the extended hub.

Fig. 4 shows a modification of the inner cutting cylinder. Instead of the cutting knives being cast in one with the cylinder, the latter one is provided with the thin sheet 50 steel cover 24, made in one piece, or in segments, and fastened to the outer surface of the inner cylinder by countersunk setscrews, or soldered on, the sharp edges on the slots of the sheet forming the cutting knives, 55 which can thus be removed and re-sharpened, or replaced by new ones, as desired.

What I claim is:

1. A grain cutting machine, comprising a grain hopper with an offset flanged top and a tapered open flanged bottom, a stationary slotted cylinder fastened inside of said hopper, a rotating slotted cylinder with sharp cutting edges telescoping inside of said stationary slotted cylinder, a cone shaped cover holding fast in its bottom the top of said

inner cutting cylinder, a hand wheel with its hub fastened to the top of said cone shaped cover and with its rim fitting into the offset flanged top of said hopper and with radial arms connecting said rim and hub, shoveling and thrusting scoops fastened to the radial arms of said handwheel, means for supporting said hopper and for collecting the discharged grain cuttings, substantially as and for the purpose specified.

2. A grain cutting machine, comprising a grain hopper having an offset flanged top and an open tapered flanged bottom and provided with a supporting ledge at its bottom inside, a stationary slotted cylinder fastened to the bottom of said hopper, a slotted cylinder with cutting edges telescoping inside of said stationary cylinder, a cone shaped cover holding fast in its bottom the top of said inner cutting cylinder, a hand wheel fastened to the top of said cover and with its rim fitted into the offset flanged top of said hopper, shoveling scoops fastened to said hand wheel, means for supporting said hopper and for collecting the discharged grain cuttings, substantially as and for the purpose set forth.

3. A grain cutting machine, comprising a grain hopper with an offset flanged top and an open tapered flanged bottom provided with a supporting ledge inside, and a stationary cylinder resting on the bottom ledge of said hopper and fastened to same with bolts and provided with longitudinal slots with beveled edges, a rotating slotted cylinder telescoping into said stationary cylinder, a cone shaped cover holding fast in its bottom the top of said rotating cylinder, a hand wheel fastened to the top of said cover and with its rim fitted into the offset flanged top of said hopper, shoveling scoops fastened to said hand wheel, means for supporting said hopper and for collecting the discharged grain cuttings, substantially as and for the purpose described.

4. A grain cutting machine, comprising a grain hopper with an offset flanged top and an open tapered flanged bottom, a stationary slotted cylinder fastened inside of said hopper, and a rotating cylinder telescoping into said stationary cylinder and provided with longitudinal slots having sharp beveled cutting edges, a cone shaped cover holding fast in its bottom the top of said rotating cylinder, a hand wheel fastened to the top of said cover and supported with its rim on the offset top of said hopper, shoveling scoops fastened to said hand wheel, means for supporting said hopper and for collecting the discharged grain cuttings, substantially as and for the purpose specified.

5. A grain cutting machine, comprising a grain hopper with an offset flanged top and an open tapered flanged bottom, a stationary slotted cylinder fastened inside of said hop-

- per, a rotating slotted cylinder telescoping into said stationary cylinder, and a cone shaped cover with a cylindrical bottom fitting the top of said rotating cylinder and fastened to the same with bolts and provided with an offset rim at bottom overlapping the top of said stationary cylinder and terminating at its top with a shoulder and a projecting pivot, a hand wheel fastened to the top of said cover and supported with its rim on the offset top of said hopper, shoveling scoops fastened to said hand wheel, means for supporting said hopper and for collecting the discharged grain cuttings, substantially as and for the purpose set forth.
6. A grain cutting machine, comprising a grain hopper with an offset flanged top and an open tapered flanged bottom, a stationary slotted cylinder fastened inside of said hopper, a rotating slotted cylinder telescoping into said stationary cylinder, a cone shaped cover holding fast in its bottom the top of said rotating cylinder, a hand wheel fastened to the top of said cover and having radial arms with bosses cast on the same and a rim fitted into the offset flanged top of said hopper, and shoveling scoops made of twisted plates and fastened to the bosses cast on the arms of said hand wheel, means for supporting said hopper and for collecting the discharged grain cuttings, substantially as and for the purpose specified.
7. A grain cutting machine, comprising a grain hopper with an offset flanged top and an open tapered flanged bottom, a stationary slotted cylinder fastened inside of said hopper, a rotating slotted cylinder telescoping into said stationary cylinder, a cone shaped cover holding fast in its bottom the top of said rotating cylinder, a hand wheel fastened to the top of said cover with radial arms and a rim fitted in to the offset flanged top of said hopper, shoveling scoops fastened to the arms of said hand wheel, and a wooden box supporting on its top surface the bottom flange of said grain hopper and provided with a movable drawer inside for receiving the discharged grain cuttings from said rotating cylinder, substantially as and for the purpose set forth.
8. A grain cutting machine, comprising a grain hopper with an offset flanged top and an open tapered flanged bottom, a stationary slotted cylinder fastened inside of said hopper, a rotating slotted cylinder telescoping into said stationary cylinder, a cone shaped cover holding fast in its bottom the top of said rotating cylinder, a hand wheel fastened to the top of said cover with radial arms and a rim fitted in to the offset flanged top of said hopper, shoveling scoops fastened to the arms of said hand wheel, and a wooden box supporting on its top surface the bottom flange of said grain hopper and provided with a movable drawer inside for receiving the discharged grain cuttings from said rotating cylinder, substantially as and for the purpose set forth.

In testimony whereof, I have hereunto signed my name, at Syracuse, in the county of Onondaga, and State of New York, this 19th day of October, 1922.

DAVID GUELBAUM.
